GUSSET PLATE

James D. Adams, P.O. Box 113,
Colorado Springs, Colo. 80901

Filed Mar. 17, 1969, Ser. No. 16,290

Term of patent 14 years

Int. Cl. D8—04

U.S. Cl. D8—266

FIG. 1

FIG. 2

FIG. 3

FIG. 1 is a perspective view of a portion of a gusset plate illustrating four sets of punched-out teeth;

FIG. 2 is a bottom plan view of the gusset plate; and

FIG. 3 is a top plan view thereof.

I claim:

The ornamental design for a gusset plate, substantially as shown and described.
